US0D1004793S

(12) **United States Design Patent** (10) **Patent No.:** **US D1,004,793 S**
(45) **Date of Patent:** **** Nov. 14, 2023**

(54) **FACIAL TREATMENT DEVICE**

(71) Applicant: **Therabody, Inc.**, Los Angeles, CA
(US)

(72) Inventors: **Jason Wersland**, Manhattan Beach, CA
(US); **Benjamin Nazarian**, Los Angeles, CA (US); **Jaime Sanchez Solana**, Los Angeles, CA (US); **Eduardo Merino**, Los Angeles, CA (US); **Bill Webb**, San Francisco, CA (US); **Alex Zhu**, Xiamen (CN)

(73) Assignee: **Therabody, Inc.**, Los Angeles, CA
(US)

(**) Term: **15 Years**

(21) Appl. No.: **29/813,195**

(22) Filed: **Oct. 27, 2021**

Related U.S. Application Data

(63) Continuation-in-part of application No. 29/772,505, filed on Mar. 2, 2021, now Pat. No. Des. 976,431.

(51) **LOC (14) Cl.** **24-01**

(52) **U.S. Cl.**

USPC **D24/215**

(57) **CLAIM**

The ornamental design for a facial treatment device, as shown and described.

DESCRIPTION

FIG. 1 is a perspective view of a facial treatment device, showing the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures show portions of the facial treatment device that form no part of the claimed design.

1 Claim, 6 Drawing Sheets
